UNITED STATES PATENT OFFICE

147,950

DESIGN FOR A BUN WARMER

Lawrence Blazey, Cleveland, Ohio, assignor to
The Enterprise Aluminum Company, Massillon,
Ohio, a corporation of Ohio

Application July 26, 1946, Serial No. 131,998

Term of patent 14 years

(Cl. D44—1)

To all whom it may concern:

Be it known that I, Lawrence Blazey, a citizen of the United States, residing at Cleveland in the county of Cuyahoga and State of Ohio, have invented a new, original, and ornamental Design for Bun Warmer, of which the following is a specification, reference being had to the accompanying drawing, forming part thereof.

Figure 1 is a perspective view of a bun warmer in closed position showing my new design; and,

Fig. 2 is a perspective view of the bun warmer in open position.

I claim:

The ornamental design for a bun warmer, substantially as shown.

LAWRENCE BLAZEY.
